CLAIM

The ornamental design of a pager carrier, as shown and described.

DESCRIPTION

FIG. 1 is a perspective view of the pager carrier in accordance with the present invention, the strap is shown broken away to indicate indeterminate length;

FIG. 2 is a perspective view, with the pager carrier shown open: the inside of the carrier is plain and unornamented;

FIG. 3 is a front elevation view thereof;

FIG. 4 is a left side elevation view thereof;

FIG. 5 is top plan view thereof;

FIG. 6 is a right side elevation view thereof;

FIG. 7 is the rear elevation view thereof; and,

FIG. 8 is a bottom plan view.

The broken line showing of environment in FIG. 2 is for illustrative purposes only and forms no part of the claimed design.
